UNITED STATES PATENT OFFICE

EARL R. MILLER, OF CLEVELAND, OHIO

AGITATOR

Application filed February 10, 1930. Serial No. 427,143.

This invention relates to an agitator for use in connection with the slide precipitation test which is now being largely used as a substitute for the Wassermann test.

5 The principal object of this invention is to provide an agitator which may be used to agitate a small amount of liquid carried by a "grease ring" receptacle on a glass slide and which will impart thereto a motion of a substantially elliptical character in a horizontal plane.

Referring to the accompanying drawings, Fig. 1 is an elevational view of my improved agitator; Fig. 2 is a detail fragmentary view 15 of the slide holder drawn to a larger scale; and Fig. 3 is a plan view of the device shown in Fig. 1.

My improved agitator includes a base 10 having a table 11^a supported on portion 11 20 and having the upper surface thereof parallel with the lower surface of the base 10. In use the device will be set on a horizontal surface whereby the upper surface of the table 11^a will be horizontally mounted. On 25 the table 11^a are supporting rods 22 having upwardly extending portions as shown in Fig. 1. A post 16 extends upwardly from the member 11 at the end of the device opposite the supporting members 22. A pivot 30 pin 12 rigidly attached to the member 11 extends upwardly therefrom and has a pulley 13 mounted thereon. A pin 14 is carried by said pulley eccentrically thereof and is internally threaded to receive a small pin 15 about which the spring 17 is hooked. As clearly shown in the drawings, the 35 springs 17 and 23 serve to hold the slide holder 20 in proper position on the table and it should be noted that the points of 40 attachment of the springs to the members 16 and 22 are such that the slide holder is pressed slightly downwardly against the top of the table 11^a. It may be desirable in use to lubricate the contacted surfaces of the 45 slide holder 20 and table 11^a.

The slide holder 20 comprises a flat metallic member with upturned rim portions, lugs 24 to which the springs 23 are attached and the finger 21 which coacts with the pin 50 14 to impart agitating motion. A finger

opening 25 is provided for convenience in inserting and removing the slide.

As seen in the broken-away portion of Fig. 2, the slide 26 is a glass microscope of suitable dimensions and the liquid holding receptacles are provided by a ring 27 of grease applied to the slide and into which the liquid to be agitated is poured. Any convenient number of these receptacles may be employed.

While this device has been especially adapted for use in connection with the slide precipitation test, it is evident that it may be variously used in other cases where the agitation requirements are similar.

While I have shown one embodiment of my invention, I wish it understood that I am not limited to the details of such embodiment but may carry out my invention in numerous varying forms.

Having thus described my invention, what I claim is:

1. An agitator including a base, a horizontal table carried by said base, a slide holder slidable on said table, opposing spring means connected to said slide holder and normally positioning the same with respect to said table, and means carried by said base for giving to one point on said slide holder, a rotary motion in a horizontal plane.

2. An agitator including a base, a horizontal table carried by said base, a slide holder slidable on said table, opposing spring means connected to said slide holder and normally positioning the same with respect to said table, and means carried by said base for giving to one end of said slide holder a rotary motion and moving the entire slide holder in a horizontal plane only.

3. An agitator including a base, a horizontal table carried thereby, posts having attaching means, means for holding said posts in fixed relation to said table, springs attached at one end to said attaching means, a slide holder slidable on said table, said springs being attached at their other ends to said slide holder, a pulley rotatably mounted on said base and a pin carried by

said pulley eccentrically thereof and passing through a portion of said slide holder, said agitator including means constraining said slide-holder to move only in a horizontal plane.

5 4. An agitator including a base, a horizontal table carried by said base, a rotatable member carried by said base and mounted to rotate about an axis substantially perpendicular to the surface of said table, a horizontally disposed slide holder slidably associated with said table, means for pivoting one point on said slide-holder to said rotatable member eccentric to the axis thereof and means constraining the remainder of said slide-holder to a predetermined motion in a horizontal plane.

10 5. An agitator including a base, a horizontal table carried by said base, a vertical pin mounted on said base, a pulley rotatable about said pin, a second pin carried by said pulley eccentric to the axis thereof, a slide-holder slidable on said table, attaching arms carried by said table and spaced apart at 15 their ends a distance greater than the width of the slide-holder, said arms being on the side of the table opposite said pulley, a post carried by said base on the side of the pulley opposite the table, springs connecting said 20 attaching arms to spaced points on one end of said slide-holder, and a spring connecting said post with said second pin, a portion of said slide-holder being journalled on said second pin.

25 35 6. The invention defined in claim 5 wherein further the point of attachment of said springs to said arms is below the point of attachment thereof to said slide-holder.

EARL R. MILLER.
